UNITED STATES PATENT OFFICE.

MOSES M. MARCUSE, OF NEW YORK, N. Y., ASSIGNOR TO WEST DISINFECTING COMPANY, OF NEW YORK, N. Y., A CORPORATION OF NEW YORK.

SHEET-DELIVERY RECEPTACLE.

1,209,317.

Specification of Letters Patent. Patented Dec. 19, 1916.

Application filed May 12, 1914. Serial No. 838,081.

To all whom it may concern:

Be it known that I, MOSES M. MARCUSE, a citizen of the United States, and resident of the borough of Manhattan, in the city and 5 State of New York, have invented a new and useful Improvement in Sheet-Delivery Receptacles, of which the following is a specification.

My invention relates to a sheet delivery receptacle which is particularly well adapted 10 for delivering interfolded sheets of paper, as, for instance, paper towels, arranged in a stack within the receptacle.

The object of this invention is to provide 15 certain improvements in the construction, form and arrangement of the several parts of the receptacle whereby the sheets may be readily withdrawn one by one without undue friction.

20 A practical embodiment of my invention is represented in the accompanying drawings, in which—

Figure 1 represents the receptacle in perspective, the free end of the front sheet of 25 the stack being shown as projecting through the delivery slot, Fig. 2 is a vertical central section taken from front to rear through the receptacle, Fig. 3 is a horizontal section taken in the plane of the line A—A of Fig. 30 2, Fig. 4 is a vertical transverse section taken in the plane of the line B—B of Fig. 2, and Figs. 5, 6 and 7 are detail views showing the means for holding the weighted follower at the limit of its rearward movement for 35 facilitating the refilling of the receptacle.

The receptacle is of general rectangular form in cross section, its bottom being denoted by 1; its ends by 2, 3; its back by 4; its upper and lower front members by 5, 6; 40 and its cover by 7. This cover is hinged at 8 at the front of the receptacle and its free end is provided with a suitable lock 9 controlled by a key 10. The bolt 11 of the lock is arranged to project underneath the inwardly turned peripheral flange 12 which extends around the top of the receptacle. This flange 12 serves to materially strengthen 45 the receptacle at this point.

A sheet delivery slot 13 extends horizontally 50 across the front of the receptacle and it is formed between the adjacent edges of the upper and lower front members 5 and 6 of the receptacle. To facilitate the removal of the interfolded sheets and to reduce the

friction thereon, the adjacent edges of these 55 upper and lower front members 5 and 6 are curved outwardly as shown at 14, 15, to form oppositely convexed walls for the slot 13. Upper and lower inclined guide plates 16, 17, are provided at the back of the front 60 members 5 and 6 for still further eliminating the friction on the sheets as they are withdrawn from the receptacle, these guides 16 and 17 serving to bow the front sheets outwardly for facilitating their removal. 65 Rods 18, 19, extend from front to rear within the receptacle along its bottom 1, upon which rods the stack of interfolded sheets rests. These rods 18, 19, also serve to reduce the retarding friction on the sheets to a considerable degree. 70

The means for keeping the stack of sheets pressed toward the front of the receptacle comprises a weighted follower 20 having wheels 21, 22, which travel in tracks 23, 24, 75 which extend downwardly and forwardly along the ends 2 and 3 of the receptacle. The follower 20 is held temporarily at the limit of its rearward movement for facilitating the refilling of the receptacle. The 80 means which I have shown for accomplishing this result comprises a lug 25 on the follower, a hole 26 in said lug and a hole 27 in the flange 12, through which holes 26 and 27, when they are brought into alinement, a lock 85 pin 28 is inserted. This locking pin 28 may be a part of the key 10, if so desired. The ends 2, 3, of the receptacle may be provided with suitable windows 29, by means of which it may be ascertained when the supply 90 of sheets within the receptacle is nearly exhausted.

In dispensing interfolded sheets of a small size, the problems of friction do not arise to such an extent as interfolded sheets 95 of a larger size. This present receptacle is more particularly directed to dispensing sheets of a large size where friction must be eliminated to as great an extent as possible to insure the proper delivery of the sheets. 100 The features which I have described for reducing this friction, are of great value in securing the successful delivery of the sheets from the receptacle.

It is evident that various changes might 105 be resorted to in the form, construction and arrangement of the several parts without departing from the spirit and scope of my in-

vention; hence I do not wish to limit myself strictly to the structure herein set forth, but

What I claim is:—

- 5 1. An interfolded sheet delivery receptacle having a transversely arranged delivery slot through its front wall, a follower for automatically pressing the stack of sheets toward the slot, the receptacle and
- 10 follower having holes therein arranged to be brought into alignment when the follower is in its retracted position and a removable pin adapted to be inserted into said holes for temporarily holding the follower in its retracted position to permit the ready introduction of a stack of sheets into the receptacle.
- 15 2. An interfolded sheet delivery receptacle having a transversely arranged delivery slot through its front wall, inclined guide plates located within the receptacle above and below the slot, a follower for pressing the stack of sheets toward the slot, downwardly and forwardly inclined tracks located within the receptacle at the opposite ends thereof and wheels on the follower arranged to travel in said tracks.
- 20 3. An interfolded sheet delivery receptacle having a transversely arranged delivery slot through its front wall, inclined guide plates located within the receptacle above
- 25 and below the slot, a follower for pressing the stack of sheets toward the slot, downwardly and forwardly inclined tracks located within the receptacle at the opposite ends thereof, wheels on the follower arranged to travel in said tracks, a cover for the open top of the receptacle and means for temporarily holding the follower at the limit of its rearward and upward movement along the tracks when the cover is open.
- 30 4. An interfolded sheet delivery receptacle having a transversely arranged delivery slot through its front wall, a cover for the open top of the receptacle, a lock for the cover, a follower for automatically pressing the stack of sheets toward the slot and a key for the lock, said key having a pin arranged to engage the receptacle and follower when the cover is open for holding the follower in its retracted position to permit the ready introduction of a stack of sheets into the receptacle.

In testimony, that I claim the foregoing as my invention, I have signed my name in presence of two witnesses, this twenty-ninth day of April 1914.

MOSES M. MARCUSE.
